UNITED STATES PATENT OFFICE

JOHN C. HEBDEN, OF NEW YORK, N. Y., ASSIGNOR TO DYEING PROCESSES CORPORATION,
OF NEW YORK, N. Y., A CORPORATION OF NEW YORK

DYEING APPARATUS

Application filed January 18, 1928, Serial No. 82,052.

The present invention relates to improvements in apparatus of the class adapted for use in the dyeing or other treatment of yarn or other textiles while wound into cops, 5 spools, bobbins, cheeses or other package forms.

An object of the invention is to provide novel and improved means for mounting the packages and for supplying the dyeing or 10 treating fluid thereto, whereby such fluid will be caused to pass uniformly through the yarn forming each package, thereby ensuring thorough permeation of the yarn and uniform dyeing or other treatment thereof.

Another object is to provide novel and improved means for axially compressing and supporting the yarn packages whereby the 15 operations of assembling the packages in the treating chamber and the removal of the packages therefrom are facilitated, the various packages being subjected to substantially uniform axial compression, thus minimizing or preventing leakage of the treating 20 fluid at the ends of the packages and ensuring uniform flow of the treating fluid through the yarn comprising the packages.

To these and other ends the invention consists in certain improvements and combinations and arrangements of parts, all as will 25 be hereinafter more fully described, the features of novelty being pointed out particularly in the claims at the end of the specification.

In the accompanying drawings:

Figure 1 represents a section taken vertically through a dyeing or treating chamber embodying the present invention, showing the trays which support the yarn packages therein;

Figure 2 represents a section taken transversely through the dyeing chamber on the line 2-2 of Figure 1.

Figure 3 is a detail view of the upper portion of the yoke and screw partly shown in 45 Figure 1.

Similar parts are designated by the same reference characters in the several figures.

The present invention, either in whole or in part, is applicable generally to apparatus 50 suitable for use in the dyeing, mordanting,

bleaching, scouring, washing, drying or other treatment of yarn with a suitable liquor, gas or other fluid while the yarn is wound into the form of a cop, spool, bobbin, cheese or other package. In the present instance, the invention is shown and will be hereinafter described as applied to a dyeing apparatus, but it will be understood that the invention is not restricted to such use, and that modifications may be made in 55 adapting it to other uses. Furthermore, the preferred embodiment of the invention is shown in the accompanying drawings, and will be hereinafter described in detail, but it is to be understood that the invention is 60 not restricted to this particular construction as equivalents are contemplated, and such will be included within the scope of the claims.

The apparatus, according to the present invention, comprises generally a dyeing chamber or tank, and a structure embodying sets of hollow trays or similar members adapted to hold the yarn or other packages between them, said structure being adapted to be contained in said chamber and the packages to be so held between the hollow trays as to cause dye liquor or other fluid supplied to the chamber to pass uniformly through the packages to effect even dyeing or other treatment thereof, as will be hereinafter explained.

The dyeing chamber or tank comprises, in the present instance, a bottom section or base 49 and a substantially dome-shaped shell or upper section 50 which is removable with respect to the base section to enable the yarn packages to be placed preparatory to the dyeing or other treatment thereof and removed after dyeing or other treatment. As shown, the base section is provided with a ring 51 adapted to receive and form a fluid-tight fit with a flange 52 formed on a ring at the bottom of the shell 50 and a suitable number of clamping screws or bolts 53 are provided to draw these parts into contact to produce a sufficiently tight joint. A fitting 54 is secured to the bottom or base section to provide the fluid passageway 10 which communicates with the interior of the dyeing chamber, and

this fitting is provided with a flanged conduit 55, the interior of which forms the passageway 9. The passageway 10 may be connected to receive dye liquor or other fluid from a suitable source, and the passageway 9 may be connected to discharge such liquor or fluid, or vice versa. A heating coil 56 is preferably provided in the bottom or lower portion of the dye liquor or other fluid when such is desirable or required, the ends of this coil being connected to pipes 57 and 58 which may be connected to a source of supply of steam or other heating agent.

The dyeing chamber is adapted to receive a number of trays or elements between which the yarn packages are adapted to be mounted preparatory to the dyeing or other treatment thereof, and when the packages and the trays therefor have been assembled and secured the yarn packages will be subjected to axial compression which will produce substantially uniform density of the yarn throughout the packages, thus ensuring uniform dyeing or other treatment of the yarn by reason of the uniform permeation of the dye liquor or treating fluid, and the yarn packages will form at their ends substantially fluid-tight joints with the trays so that the dye liquor or other fluid forced into the dyeing chamber will be caused to flow through the yarn composing the packages without appreciable leakage at the ends thereof. Furthermore, the present invention provides a novel and improved mounting for the yarn packages whereby substantially uniform rate of flow of the dye liquor or treating fluid through all of the yarn packages is obtained. For this purpose, each end of each yarn package is engaged by and forms a fluid-tight joint with a hollow tray, the interiors of the series of trays inter-communicating so that the pressure of the dye liquor or treating fluid will be substantially equal at the interior of each yarn package and at both ends of its interior bore.

In the construction shown, a set of trays 59 and a bottom tray 60 are shown, the trays 59 all being duplicates, and the bottom tray 60 being generally similar to the trays 59, but modified to adapt it to seat on the flange of the conduit 55. The bottom tray comprises upper and lower plates 61 and 62 which are spaced to form an interior chamber 63, and these plates are rigidly connected at suitable points by stay members 64. A fitting 65 having a flange 66 is secured to the bottom of the tray 60, the flange 66 being adapted to rest in a groove 67 formed in the top of the flange 68 on the upper end of the conduit 55 to form a substantially fluid-tight joint therewith. The inner portion of the fitting 65 is webbed or otherwise formed to enable the dye liquor or treating fluid to pass vertically through it. A plate 69 is fixed on the upper side of the tray 60, it having a groove 70

therein to receive the joint-forming flange for the tray next above it. Each of the trays 59 has a ring 71 fixed to it and containing a packing gland 72 adapted to receive packing material 73 between it and the ring 71, the lower edge of the packing gland providing the flange which engages in the groove 70. The upper side of each of the trays 59 is provided with a plate 74 which is similar to the plate 69 on the upper side of the tray 60, it having a groove 75 therein to receive the lower edge of the packing gland of the tray next above it. The packing glands 72 of all of the trays are webbed or otherwise formed to permit the passage of the dye liquor or other treating fluid therethrough. The lower and upper plates 76 and 77 composing each of the trays 59 are spaced to form an interior chamber 78, and these plates are connected together at suitable points by stay bolts or other suitable means to maintain them in properly spaced relation.

The trays are so constructed that they will receive the ends of the yarn packages between them and will form substantially fluid-tight joints with the ends of the packages. As shown, cup-shaped seats 79 are applied to opposite faces of each tray, these seats being adapted to receive and form joints with the ends of the yarn packages, the seats having apertures 80 therein to receive the ends of the holders 81 on which the yarn is wound. Holders of different kinds may be used, although these holders are of a size to fit the holder or bore in the wound yarn and the holder is pervious to permit the dye liquor or other treating fluid to flow therethrough without substantial obstruction. When the ends of the holders which are of sufficient length to project beyond the ends of the yarn packages are inserted in the central openings 80 in the seats on the trays, the yarn packages will be properly centered with respect to the seats and held in such position. The yarn holders are tubular or hollow and open at the ends, and when the yarn packages have been applied to the trays, the interior passages through the tubular or hollow yarn holders will have unobstructed communication with the interior chambers within the trays, it being noted that the ends of the holder of each package will directly communicate with the interior chamber of a tray.

After the yarn packages have been placed between each pair of trays, such trays are held together by suitable means. Preferably, a series of shouldered bolts 82 is provided for this purpose. The lowermost bolt may be threaded at its lower end in the member 65 on the bottom of the lowermost tray, while the shoulder 83 of this bolt bears on the upper side of the gland 72 of the tray next above it, but the bolt 82 of the next tray and the bolts for the remaining trays of the se-

ries are threaded into the upper ends of the bolts next below them. In addition, in order to distribute more evenly the compression maintained by the trays upon the yarn packages interposed between them, series of bolts 84 similar to the bolts 82 may be extended through tubes 184 which form openings in the portions of the trays between the center and the periphery thereof and at circumferentially spaced intervals around the trays, these additional bolts being accommodated in the spaces left between the rows of yarn packages. After each pair of trays have been assembled with the yarn packages between them, they are subjected to axial compression, as, for example, by a suitable press, thus compressing the yarn packages axially to render uniform the density of the yarn composing each package and to form substantially fluid-tight joints between the ends of the yarn packages and the trays and while the pair of trays are thus compressed, the bolts 82 and 84 are tightened, thus holding the packages under compression. The several trays containing the yarn packages are assembled in a stack and held together by the series of connected bolts 82 and 84 which extend continuously through all the trays in the stack. The stack of trays may then be placed in the treating chamber.

Means are also provided for preventing floating of the pile of trays and the interposed yarn packages and to retain the flange 66 in fluid-tight relation with the flange on the upper edge of the conduit 55. Preferably, such means comprises a yoke 85 which may be bolted or otherwise fixed to the top of the dyeing chamber and a screw 86 extends through a bushing 87 which is revolvable in the top of the yoke and has a thread engagement with the screw, the bushing being provided with a hand-wheel 88 for rotating it. By this arrangement, rotation of the hand-wheel and bushing in one direction will force the screw 86 downwardly, and the screw extends through a stuffing box 89 in the top of the dyeing chamber and bears at its lower end on a bolt 90 which cooperates with a head 91 to exert the compression on the yarn packages between the topmost tray and the tray next below it. By rotating the hand-wheel in a direction to force the screw 86 downwardly, the pile of trays will thus be forced downwardly, thus retaining the flange 66 in proper contact with its seat on the top of the conduit 55. Before the screw 86 is thus adjusted, the clamping bolts 53 which hold the shell or upper section 50 in place, are tightened.

When the trays containing the yarn packages are assembled in the dyeing chamber, the webbed member 65 and webbed glands 72 will form a continuous passageway from top to bottom of the assembled trays and in the center thereof for the flow of the dyeing liquor or other treating fluid, and this cen-

tral passageway will provide inter-communication with the interior chambers of the various trays. Furthermore, this central passageway through the trays and the hollow chambers within the trays is in communication with the passageway 9 at the bottom of the dyeing chamber, and this latter passageway and the passageway 10 may be connected to any suitable or well known piping, circulating pump and tank system for supplying the dye liquor or other fluid to and removing it from the yarn dyeing or treating chamber. When the dye liquor or treating medium is delivered to the passageway 10, such liquor or fluid will be forced into the portion of the dyeing chamber exteriorly of the trays and will reach the exteriors of the yarn packages which are held and compressed between the trays. This dye liquor or treating fluid is forced into the dyeing chamber with sufficient pressure to force it through the yarn composing the packages from the outside to the center thereof, and the dye liquor or treating fluid after reaching the centers of the yarn packages enters the pervious holders which form cores therefor, and the dye liquor or fluid then flows through the ends of the holders into the interior chambers of the trays, thence to the central passageway through the trays to the passage 9, and it returns to the circulating pump.

The direction of circulation of the dye liquor or fluid may be reversed, in which case, the liquor or fluid enters the dyeing chamber through the passage 9 and flows upwardly through the central passageway in the trays, part of this liquor being diverted into the interior cavities or chambers in the trays, thence flowing into the pervious or hollow holders which extend through the yarn packages, and the liquor or fluid is then forced outwardly through the yarn composing the packages, and upon reaching the outside of the packages, flows into the passage 10, and finally returns to the suction side of the circulating pump.

After the packages of yarn have been properly dyed or otherwise treated, the shell or upper section 50 of the dyeing chamber is lifted from the base, thus exposing the pile of trays and the yarn packages interposed between them, and by loosening successively the central bolts 82 and also the supplemental bolts 84 and lifting the trays, the dyed or treated yarn packages are removed, the apparatus being then ready for the mounting and dyeing or other treatment of another supply of yarn packages.

While the invention has been described in connection with the dyeing or similar treatment of packages of yarn, it is to be understood that the invention is applicable also to packages of textile materials of other kinds such, for example, as roving, slubbing, laps and so forth.

I claim as my invention:—

1. In an apparatus for treating packages of textiles with fluids, trays to receive the packages between them, and means for holding them in variable spaced relation to compress the interposed packages, the trays having interior fluid passages which communicate with the ends of the packages. 70
2. In an apparatus for treating packages of textiles with fluids, hollow trays to receive the packages between them and to form fluid connections with their ends, and means for holding the trays in variable spaced relation to maintain the interposed packages under compression, the interior chambers of the trays communicating with the respective ends of the packages. 75
3. In an apparatus for treating packages of textiles with fluids, opposed hollow trays relatively movable to compress the packages between them and to form fluid connections with the respective ends thereof, and means for maintaining fluid communication between the interior chambers of the trays. 80
4. In an apparatus for treating packages of textiles with fluids, cooperative hollow trays adapted to receive the packages between them, means for relatively drawing the trays toward one another to axially compress the packages and form fluid-tight connections between their ends and the respective trays, and means for maintaining a fluid-tight connection between the interiors of the relatively movable trays. 85
5. In an apparatus for treating packages of textiles with fluids, relatively movable cooperative hollow trays having apertured seats on their opposed faces to individually receive the packages and to form fluid connections between their interior chambers and the respective ends of the packages, and means for variably spacing apart the trays. 90
6. In an apparatus for treating packages of textiles with fluids, cooperative relatively movable hollow trays having means to form fluid connections between their hollow interiors and the respective ends of packages interposed between them and having means for interconnecting their hollow interiors. 95
7. In an apparatus for treating packages of textiles with fluids, the combination of a treating chamber having fluid inlet and outlet passages, and a set of hollow trays to receive the packages between them and form fluid connections between their hollow interiors and the ends of the packages, and means for establishing fluid connections between the hollow interiors of the trays and one of said passages of the treating chamber. 100
8. In an apparatus for treating packages of textiles with fluids, the combination of a treating chamber having fluid inlet and outlet passages, a series of hollow trays adapted to receive the packages between them and to form fluid connections between their hollow
- interiors and the ends of the packages, means for establishing fluid connections between the hollow interiors of the trays and one of said fluid passages of the treating chamber, and means for drawing together the trays to axially compress packages interposed between them. 105
9. In an apparatus for treating packages of textiles with fluids, the combination of a treating chamber having fluid inlet and outlet passages, one of said passages having a seat therefor, a series of superposed hollow trays adapted to receive the packages between them and to form fluid connections between their hollow interiors, and the ends of the packages, joint-forming means for interconnecting the hollow interiors of the trays with one another, said means forming a fluid-tight joint with said seat, means for drawing together the trays to axially compress packages interposed between them, and means operative to hold the trays in engagement with said seat. 110
10. In an apparatus for treating packages of textiles with fluids, the combination of a treating chamber having a fluid passage and a seat surrounding it, a stack of package-holding trays supported on said seat, means for individually drawing together adjacent trays to compress the packages interposed between them, and means operative on the stack of trays to hold them on said seat. 115
11. In an apparatus for treating packages of textiles with fluids, the combination of a treating chamber having a pair of separate fluid passages one of which is provided with a surrounding seat, means for circulating fluid to cause it to enter said chamber through one of said passages and to discharge therefrom through the other passage, or vice versa, a set of hollow trays adapted to be mounted in superposed relation, one upon another, to form a stack to rest on said seat, and means for interconnecting the hollow interiors of the trays with one another and with the fluid passage which is surrounded by the seat. 120
12. In an apparatus for treating packages of textiles with fluids, the combination of opposed hollow trays, pervious holders to contain textile packages interposed between the trays, the ends of each package and the pervious holder thereof forming fluid connections with the respective trays, and means for variably spacing apart the trays. 125

In testimony whereof I have hereunto set my hand.

JOHN C. HEBDEN.
